UNITED STATES PATENT OFFICE.

OSBORN B. HALL, OF MALDEN, MASSACHUSETTS.

MACHINE FOR TAPPING MAINS.

SPECIFICATION forming part of Letters Patent No. 358,445, dated March 1, 1887.

Application filed December 11, 1886. Serial No. 221,329. (No model.)

To all whom it may concern:

Be it known that I, OSBORN B. HALL, of Malden, in the county of Middlesex and State of Massachusetts, have invented a new and useful Improvement in Machines for Tapping Water-Pipes Under Pressure, which will, in connection with the accompanying drawings, be hereinafter fully described, and specifically defined in the appended claims.

10 This invention relates to mechanism for tapping water-pipes under pressure; and it consists in the construction and combination of divers devices embodied therein, as herein-after more particularly and fully set forth and 15 claimed.

In the drawings, Figure 1 is a perspective view of a machine embodying my invention, shown as secured to the water-pipe. Fig. 2 is a sectional plan view, the section being 20 horizontal and taken as on line X X, Fig. 3, and the view being as from above that line. Fig. 3 is a longitudinal sectional elevation, the section being taken as on line W W, Fig. 2, the water-pipe being also shown in section.

25 In said views, A represents the water-pipe, and B the body or reservoir, of my tapping mechanism, the bottom of which latter is shown as formed with a base rim or flange, a, between which and pipe A is interposed the 30 packing-ring or gasket b, which is compressed in place by means of clamping chains C, attached to the ends of bars e, which bear upon lugs d of body B. At the top of B is a circular plate, e, which rests in a concentric seat in 35 the wall of B, and is held in position by the flat ring f, which, by means of screws v, Fig. 1, serves to press the packing-ring g firmly in place. In plate e the drill-tap h and carrier i are respectively journaled equidistant from 40 the center, and are each provided with a stuffing-box, t, for packing the joint between them and the plate.

The carrier i is formed, as shown, to receive the threaded stud of stop-cock j, which latter 45 is threaded at its lower end to enter the threaded hole k in pipe A as left by tap h.

Two standards, l, secured in lugs formed upon body B, support and secure in place the

cross-bar m, in which is threaded the depressing-screw n, actuated by its hand-wheel p, and 50 which is arranged to act upon drill-tap h and carrier i, as they are respectively brought beneath said screw. A lever-ratchet, q, is shown as employed to actuate said drill-tap and carrier. Said plate e is revolved in its seat by 55 means of a spanner or lever engaged with studs u, formed upon the plate for that purpose; but when the water-pressure in the pipe being tapped is considerable, the upward pressure upon and resulting friction of plate e is such 60 as to render great force necessary to revolve it, thus quickly destroying packing g; and to obviate this I arrange in bar m an adjustable stud, s, to bear in a central seat in said plate e, and which, by being properly adjusted, 65 will receive nearly all the upward pressure that is exerted upon said plate, so that it may be revolved with but a trifling expenditure of force and without injury to packing g.

I am aware that a pipe-tapping mechanism 70 having a hollow body or tank, with means for clamping it to the water-pipe, and having a rotary disk carrying a drill-tap and carrier for the cock, with means for actuating them, are not new; hence I do not claim them as my 75 invention; but

I do claim as follows, to wit:

1. The combination, with a pipe-tapping machine arranged to operate substantially as described, of a stud arranged to be forced 80 downward upon the center of the rotary tool-carrying plate thereof, substantially as specified.

2. In a pipe-tapping machine, the combination, with body A, bar m, supported above 85 and by said body, rotary plate e, carrying the drill-tap and carrier i, and means for depressing said tools, of stud s, arranged to be forced against the center of said plate and to resist the upward pressure thereon, substantially as specified.

OSBORN B. HALL.
